UNITED STATES PATENT OFFICE.

ELLEN W. STILES, OF GRAND RAPIDS, MICHIGAN.

UNDERWAIST.

No. 901,046.

Specification of Letters Patent.

Patented Oct. 13, 1908.

Application filed September 9, 1907. Serial No. 391,945.

To all whom it may concern:

Be it known that I, ELLEN W. STILES, a citizen of the United States of America, residing at Grand Rapids, in the county of Kent and State of Michigan, have invented 5 certain new and useful Improvements in Underwaists; and I do hereby declare the following to be a full, clear, and exact description of the invention, such as will enable others skilled in the art to which it 10 appertains to make and use the same.

My invention relates to improvements in underwaists, and its object is to provide the same with detachable elastic portions, 15 whereby the said portions may be removed and the remainder of the waist subjected to washing and boiling, which operation would materially injure the elastic portions if they were not removed; to provide means 20 whereby the elastic portions of the waist may be removed and like new portions substituted as occasion requires; and to provide the device with various new and useful features, hereinafter more fully 25 described and particularly pointed out in the claim, reference being had to the accompanying drawings, in which:

Figure 1. is a side elevation of a waist embodying my invention; Fig. 2. a detail of 30 one of the shoulder straps of the same, shown in plan view; and, Fig. 3. an edge view of the same.

Like numbers refer to like parts in all of the figures.

35 1 represents the front portion of the waist and 2 the back part of the same. Between these portions and below the arm hole, at each side, is inserted a detachable elastic portion comprising eyelet strips 6 having eyelets 7 arranged opposite a corresponding 40 row of eyelets 5 in the respective front and rear portions, these strips being attached to said portions by means of lacing 8. Said strips are also connected by a series of elastic 45 tapes 11 whereby the garment is made yieldable at the sides and more comfortable for the wearer. Above the arm holes are shoulder straps 9 also of elastic material

and detachably connected at the front and rear portions by any suitable fastenings, 50 preferably by ball and socket fastenings 10. These shoulder straps are preferably covered by some pliable material 3, which is Shirred or gathered as indicated, to permit of the longitudinal expansion of the shoulder strap 9. This material renders the device more comfortable for the wearer, makes a finish for the garment where it passes over the shoulder and permits expansion and contraction of the straps 9. These elastic and 60 yieldable portions 9 and 11 are preferably of elastic tapes which depend for their elasticity upon inserted strips of rubber, which rubber would be injured by the boiling or other washing process necessary to wash the 65 front and rear portions of the garments. These tapes also by use become stretched and the rubber ultimately fails to contract, and needs to be replaced. This can be quickly done by removing these detachable 70 portions and substituting new ones therefor. I am thus able to readily wash or repair the garment and at the same time provide elastic portions therein, which renders the same much more comfortable for the wearer, and 75 yieldable to the various movements of the body as occasion requires.

What I claim is:

In a garment, front and rear portions spaced apart at and beneath the arm-holes, 80 each portion having a series of eyelets in each adjacent edge, lacing strips having corresponding lacing eyelets, lacings for the eyelets to secure the respective strips to the respective edges, the front and rear portions 85 each carrying a socket, a shoulder strap having a projection at each end for engagement in the sockets of the front and rear portions, a covering for said strap, and flexible connections between said lacing strips. 90

In testimony whereof I affix my signature in presence of two witnesses.

ELLEN W. STILES.

Witnesses:

GEORGINA CHACE,
LUTHER V. MOULTON.
